CONTAINER

Edwin J. Schoettle, Philadelphia, Pa., assignor to
 Edwin J. Schoettle Company, Philadelphia, Pa.,
 a corporation of Pennsylvania

Application August 2, 1934, Serial No. 738,123

4 Claims. (Cl. 229—44)

This invention relates to containers formed of cardboard or similar material and more particularly to that type of container which is constructed of several pieces of material connected together in the process of forming the container.

An important object of the invention is to provide a joint or lock between these sections formed from the material of the sections and readily assembled, which, by means of a single connection, securely locks the sections against relative movement in all directions.

A further and more specific object of the invention is the provision of a slip and tab connection between the container sections of this character or between any two similar sections which it may be desired to connect, which provides a multiplicity of shoulder abutments between the sections so arranged that they resist relative movement of the sections in any direction.

These and other objects, I attain by the construction shown in the accompanying drawing, wherein

Fig. 1 is a fragmentary prospective view of the container, the lid and body of which are formed of two separate sections connected in accordance with my invention;

Fig. 2 is an enlarged sectional view on line 2—2 of Fig. 1;

Fig. 3 is a plan view of one of the sections showing the joint element formed therein; and

Fig. 4 is a plan view of the other section showing the joint section formed therein.

Referring now more particularly to the drawings, of the elements A and B, which which are to be connected, the element A is formed with an opening 10, the material of which may be either removed or left in the form of a flap F as illustrated in the present instance. The form of the opening may be varied as desired but must provide corners 11 spaced transversely of the sheet and wall portions 13 which are spaced longitudinally of the sheet from a line connecting the corners 11 and are more or less opposed to one another in a direction transverse to the sheet.

The section B is formed with a shallow tab 14 providing shoulders 15 facing away from one another transversely of the sheet and adapted to engage at the junction of the margins of the tab, with the section B against the wall portions 13 and is formed with a second tab means 16 embodying the shoulders 17 facing away from one another transversely of the sheet and adapted to engage in the corners 11 of opening 10.

Tab means 16 may be either unitary or in the form of two distinct tabs as desired and in the assembly of the sections, the shoulders 17, which are provided thereby, are first engaged in the corners 11 of opening 10. It may be here pointed out that if the flap F is left attached as herein shown, it will assist in guiding the shoulders 17 to their proper location, particularly if the walls 13 are divergent as herein illustrated. This flap will also serve to reinforce the tab means 16 against inward flexing. When the shoulders 17 are properly seated in the corners, the flap 14, which has its lower terminal with at least one point spaced a greater distance longitudinally of the sheet from the adjacent ends of the shoulders 17 than the now opposed portion of opening 10, is forced over the edge of the opening so that the junction of the shoulders 15 with the section B will engage against the opposed walls 13 and shoulders 17 will overlap the edge of the opening 10.

It will be seen from an inspection of Fig. 1 that longitudinal pressure downwardly upon the section B adjacent the upper edge of the section A will be resisted by engagement of the shoulders 15 with the lower wall of the opening and similarly an upward pull at this point will be resisted by the engagement of the shoulders 17 against the upper wall of the opening at the corners 11. Any attempt to rotate the section B with relation to the section A will be resisted by one or the other of the shoulders 15 and the diagonally opposed shoulder 17 so that a complete locking connection of the two sections is provided. While tab 14 is disclosed as formed at the lower marginal edge of the section, it might obviously be formed inwardly of such edge if so desired.

Since the construction is capable of considerable modification without in any manner departing from the spirit of my invention, I do not wish to be understood as limiting myself thereto except as hereinafter claimed.

I claim:

1. Connected sections of a cardboard container or the like wherein one section has an opening affording transversely spaced opposed corners and transversely spaced walls opposing one another at a point spaced longitudinally of the section from said corners, the other section having tab means affording shoulders transversely spaced thereon a distance equal to the distance between said corners and engaged therein, and a second tab means affording shoulders spaced transversely of said second section and engaged

- and fitting between the opposed walls of the opening of the first member, at least a portion of the last-named tab means being spaced longitudinally of the second section from the first-named shoulders a distance such that it overlaps the confronted edge of the opening of the first section intermediate the points of engagement of the last-named shoulders with said opposed wall portions. 5
- 10 2. Connected sections of a cardboard container or the like wherein one section has an opening affording transversely spaced opposed corners and transversely spaced walls opposing one another at a point spaced longitudinally of the 15 section from said corners, the other section having tab means affording shoulders transversely spaced thereon a distance equal to the distance between said corners and engaged therein, and a second tab means affording shoulders spaced transversely of said second section and engaged and fitting between the opposed walls of the opening of the first member. 10
- 15 3. Connected sections of a cardboard container or the like wherein one section has an opening affording transversely spaced opposed corners and transversely spaced walls opposing one another at a point spaced longitudinally of the 20 section from said corners, the other section having tab means affording shoulders transversely spaced thereon a distance equal to the distance between said corners and engaged therein, a second tab means affording shoulders spaced 25 transversely of said second section and engaged and fitting between the opposed walls of the opening of the first member, and means on the first section reinforcing the first-named tab means to prevent displacement thereof through the opening between the said corners. 25

EDWIN J. SCHOETTLE.
